OVERSPEED DEVICE

Charles M. Bovard, Grove City, Pa., assignor to
 Cooper-Bessemer Corporation, Mount Vernon,
 Ohio, a corporation of Ohio

Application August 12, 1931, Serial No. 556,471

4 Claims. (Cl. 123—32)

The invention relates to internal combustion engines of the type wherein fuel under pressure is injected into the engine cylinders, and has for a general object to supplement the usual regulating system of the engine by providing a safety device which operates upon the occurrence of abnormally high engine speed, to reduce the pressure on the fuel line to a low value, thereby safeguarding the engine against injury in case the ordinary fuel regulating system should fail to operate properly.

Diesel engines, for example, are in common use wherein fuel oil under pressure is supplied from a common manifold to the various cylinders through branch connections in which are located mechanically actuated valves which are controlled by a speed governor, to admit quantities of fuel regulated according to the speed of the engine. And in applying the present invention to Diesel engines, a safety device is employed which under abnormally high speed conditions automatically reduces the fuel pressure in the manifold to a low point, preventing further overspeeding; however, a fairly low pressure is preferably maintained in the manifold under such conditions, to prevent the fuel system from becoming air bound. It should be understood that the principles of the invention are applicable to other internal combustion engines wherein liquid or gaseous fuels are supplied under pressure.

Further objects and advantages of the invention will be in part obvious and in part specifically referred to in the description hereinafter contained which, taken in conjunction with the accompanying drawings discloses a preferred embodiment of the invention. Such embodiment, however, is to be considered as merely illustrative of the principles of the invention. In the drawings—

Fig. 1 is a view partly in section and more or less diagrammatic of an overspeed device adapted to operate in accordance with the invention.

Fig. 2 is a sectional view showing such device in relation to a typical engine assembly.

The invention is disclosed as applied to a Diesel engine of the type above referred to wherein oil is maintained under injection pressure in a manifold 18 from which branch pipes 16 lead to the various cylinders; suitable means is provided regulating the amounts of fuel supplied to the cylinders under different operating conditions. In applying the present invention to an engine of the above type, an overspeed device is employed having an overspeed valve connected to the manifold 18, which remains closed or inactive under

normal operating conditions, but which is actuated under abnormally high engine speeds, to relieve the pressure within the manifold 18.

As shown in Fig. 1, for example, this overspeed valve includes a casing 36 in which operates a sliding valve 37 having a reduced portion 38 which connects the ports 39 and 40 when valve 37 is raised. The port 39 is connected by a pipe coupling 41 and pipe 42 to the fuel manifold 18 and the port 40 is connected by a pipe 45 to the source of fuel, and hence when valve 37 is raised as above described, the fuel pressure in manifold 18 may be relieved. The port 40, however, is normally closed by a relief valve 43 which also closes a port 44 communicating with the pipe 45 as above mentioned. A spring 46 may be adjusted by the threaded plug 47 to control the pressure at which the relief valve operates. As shown, a cap 48 is threaded on the exterior of the plug 47.

The position of the valve member 37 is controlled according to the speed of the engine by any suitable type of speed governor, such as responsive mechanism indicated diagrammatically at 60 in Fig. 1. It will be understood that this valve may be operated from the speed governor such as commonly employed in engines of the above type, although I prefer to employ a separate governor for this purpose, to insure the relief of pressure on the fuel line in case the usual governor should be out of order.

The valve 37 is moved by the governor 60 in such manner as to connect the ports 39 and 40 upon the occurrence of a predetermined abnormally high engine speed and under these conditions the fuel pressure in manifold 18 will be high enough to unseat the relief valve 43, thus relieving the pressure in manifold 18 down to a point at which spring 46 moves the valve 43 to closed position. In applying the invention to Diesel engines, the spring 46 is preferably set to return valve 43 to closed position at a fuel pressure somewhat above or at least equal to atmospheric pressure, to prevent air from getting into the fuel line. In fact the pressure drop in manifold 18 caused by the operation of the overspeed device, need not be so great as to stop the engine entirely, but merely sufficient to prevent continued operation at unduly high speed.

In Fig. 2 the overspeed device above described is shown in relation to a Diesel engine assembly which should be regarded as merely typical and it will be understood that the invention is not limited in its application to engines of this par-

20

ticular type. In the particular form of engine shown in Fig. 2, a casing 10 is provided with any suitable number of cylinders, one of which is shown in cross section at 11. Operating in each cylinder is the usual piston 12 connected by a piston rod 13 to a crank shaft 14. Each cylinder is equipped with an injection valve 15 connected by a pipe 16 equipped with a cut-off valve 17, to a high pressure common manifold 18, to which fluid under pressure is supplied by a pump 19, which draws fuel from a fuel supply tank 20 and delivers it under pressure through a pipe 21 to the common manifold 18. The pump 19 is operated from the crank shaft by means of a sprocket chain 22 driven by a sprocket wheel 23 connected to a gear wheel 24 meshing with a gear wheel 25 on the crank shaft 14. The sprocket chain, as indicated passes over a sprocket wheel 26 which by suitable driving connections, as indicated, operates the pump 19. The sprocket chain 22 also passes over a sprocket wheel 27 secured on the cam shaft 28 which carries cams 29 operating on rollers on reciprocating plungers 30 which operate bell cranks 31 connected to the needle 32 of the injection valve 15.

A wedge 33 controlled by the governor 34 and lying between the plunger 30 and the bell crank 31 controls the amount of fuel injected. The construction is such that as the load on the engine increases and its speed decreases, the wider portion of the wedge 33 is moved in between the plunger and the bell crank to cause the valve to be lifted higher to increase the amount of fuel oil delivered at each injection, and as the speed increases the wedge is withdrawn to reduce the amount of fuel oil delivered at each injection, thus limiting the speed of the engine when not under load.

The governor 60 shown diagrammatically in Fig. 1 may be regarded as contained within the housing 35 of Fig. 2, and driven in any suitable manner, as by sprocket 65 (Fig. 2) meshing with chain 22. The overspeed valve casing 36 is shown mounted upon the housing 35, with the pipe 42 connected to the pipe 41 which leads to the manifold 18, and the pipe 45 connected to the fuel supply tank 20.

As shown in Fig. 2 the valve casing 36 may also be provided with a passageway 76 communicating with port 44 and leading to the space around the bottom of valve stem 37, so that any fuel which leaks past the valves may be carried

away through the pipe 77 indicated at the bottom of Fig. 1.

While the invention has been described with reference to a preferred form of relief valve and operating means therefor, it is to be understood that changes which may be made in the construction thereof without departing from the spirit of this invention, are comprehended within the terms of the appended claims.

I claim:

1. The combination with an engine of the class described of a fuel line adapted to supply fuel under pressure to the engine cylinders, speed controlled means for regulating the amounts of fuel so supplied, a separate speed responsive mechanism, and means actuated by said speed responsive mechanism under abnormally high speed conditions for relieving the pressure in said fuel line, said last mentioned means including a valve acting to limit the degree of such pressure relief.

2. The combination with an engine of the class described, means for delivering fuel under pressure to the engine cylinders, means for regulating the amounts of fuel so supplied, a relief valve adapted to be operated by the fuel under pressure for reducing the pressure of the fuel, and means automatically operable as the engine attains a predetermined speed for establishing communication between the fuel under pressure and the relief valve to operate the relief valve.

3. The combination with an engine of the class described, of a fuel line adapted to supply fuel under pressure to the engine cylinders, means for regulating the amounts of fuel so supplied, and means responsive to speed conditions for relieving the pressure in said fuel line below the normal pressure under abnormally high speed conditions and for restoring normal pressure under normal speed conditions.

4. In combination with an engine of the class described, of a fuel manifold connected to the engine cylinders to supply fuel thereto, means for supplying fuel under pressure to said manifold, means for regulating the amounts of fuel so supplied to the cylinders, a valve connected between said manifold and a point at lower pressure, and means responsive to speed conditions for opening and closing said valve respectively to relieve the pressure in said manifold under abnormally high speed conditions and to restore normal pressure under normal speed conditions.

CHARLES M. BOVARD.
